UNITED STATES PATENT OFFICE.

HENRY BERRY, OF SHELTON, CONNECTICUT, ASSIGNOR TO THE DERBY SILVER COMPANY, OF SAME PLACE.

DESIGN FOR A DISH OR BASKET.

SPECIFICATION forming part of Design No. 20,197, dated October 14, 1890.

Application filed September 16, 1890. Serial No. 365,200. Term of patent 7 years.

To all whom it may concern:

Be it known that I, HENRY BERRY, a citizen of the United States, residing at Shelton, in the township of Huntington and State of Connecticut, have invented and produced a new and original Design for a Dish or Basket, of which the following is a specification, reference being had to the accompanying drawing, forming part thereof and illustrating the said dish or basket in perspective.

The leading feature of my design consists in the dish or basket having the irregular edge and representing a portion of an egg, with a wish-bone carried thereby, as shown in the drawing.

A designates the body of the dish or basket; B, the wish-bone carried thereby, and C the irregular edge, indicating a broken egg-shell. The outline of the dish or basket is that of about one longitudinal half of an egg with a broken edge, the opposite side edges being somewhat below the horizontal plane of the ends. The dish or basket is provided with a handle D, suitably ornamented, and with

the two spherical legs E, which are at the rear portion of the dish or basket, and hence serve as supports and to tilt the front and narrower portion of the same slightly forward.

The rear portion of the dish or basket bears the floral and foliate ornamental scroll F and the words "Best Wishes," while the transverse center of the basket is traversed by the ornamental band G, composed of the conventionalized foliate scroll H. The leading feature of the design, however, consists of the dish or basket in the outline of one longitudinal half of an egg with the irregular edge and the wish-bone.

What I claim is—

The design for a dish or basket, substantially as shown and described.

Signed at Shelton, Connecticut, this 13th day of September, 1890.

HENRY BERRY.
